WALTER SCHWEITER, OF HORGEN, NEAR ZURICH, SWITZERLAND

LOCKING DEVICE, MORE PARTICULARLY FOR TEXTILE MACHINES

Application filed December 4, 1930, Serial No. 500,125, and in Germany January 18, 1930.

The invention relates to locking devices more particularly intended for textile machines.

In these machines, especially in winding machines, locking devices, are employed the object of which is to cause the yarn guide or the yarn guide carrier to easily give way in one direction in accordance with the increase of the yarn layers wound on the bobbin, and to be locked in the opposite direction of motion. In locking devices of this class generally locking members are made use of such as balls, rollers, wedges or the like which co-operate with a guide member, for instance a bar, in such a manner that they are loosely entrained in the one direction but upon motion in the opposite direction are clamped between the guide bar and an internally tapering sleeve surrounding the device whereby a motion of the yarn guide in this direction is prevented.

Now it has been found that by these locking members which in order to work satisfactorily are made from hardened steel, the guide bar is worn out in the course of time, by longitudinal grooves being engraved therein which not only impair the appearance of the machine but under circumstances grow so deep as to harm the correct working of the locking device. The invention has therefore for its object to overcome these drawbacks.

This object is achieved primarily by the fact that a member is interposed between the locking members, such as balls, rollers, wedges or the like, and the guide member along which the member to be locked is moving, which interposed member takes up the pressure exerted by the locking members and distributes it on a large surface of the guide member. Advantageously an elastic ring is employed for this purpose which is shiftably arranged on the guide bar of the device and is held in position in a recess of the cage in which the locking members rest, the latter exerting their pressure upon the outer

surface of this ring. In this way the locking pressure is not transmitted immediately to a few individual places of the guide bar, but to the entire circumference thereof and in the width of the interposed member, so that any deformation of the guide bar is excluded. Furthermore, the resilient ring favors the release of the locking device because it tends to move the locking members radially outwardly, that means to lift them from the guide bar.

In order that the invention may be more readily understood, a preferred embodiment of the locking device according to the invention is illustrated by way of example in the accompanying drawing which shows on an enlarged scale a vertical section through the locking device of a type intended to be used in bobbin winding frames.

The device comprises an internally tapering cap 1 screwed onto a sleeve 3 which is shiftable on the guide bar 2, and another sleeve 5 likewise shiftable on bar 2 and forming the cage for the locking balls 4 which are distributed on the entire circumference of bar 2. Between sleeve 3 and sleeve 5 is provided a coiled spring 6 while a ring 7 is mounted on the outer surface of sleeve 5 which ring serves as a handle for easily disassembling the device. Sleeve 3 is rigid with the front plate 12 guided by a bar 11 and having mounted on it the cone 13 that cooperates with the bobbin to be wound.

Now the balls 4 distributed on the circumference of sleeve 5 are not in immediate contact with the guide bar 2, as in the locking devices hitherto employed, but act upon a ring 8 interposed between them and bar 2, and made from steel or any other suitable material. The ring 8 rests in an annular recess 9 of sleeve 5 and has an inclined slot 10 so as to be resilient in outward direction. When the locking device is in working condition that means when the balls 4 are pressed by the spring 6 into the tapering bore of cap 10

1, acting as a clamping member, their pressure is not transmitted immediately to the bar 2, but to the elastic ring 8 by which the pressure is uniformly distributed on the entire surface of bar 2 covered by it, so that any deformation of bar 2 is excluded. Upon disengaging the locking device by shifting sleeve 5 toward the right, the elasticity of ring 8 enters into action and tends to lift the balls 4 radially and thus to release bar 2.

In lieu of the balls 4 of course cylindrical or conical rollers, wedges or the like may be made use of which act like the balls and hitherto have cooperated immediately with the guide bar 2. In such a design too the pressure exerted by these locking rollers etc. can be distributed on a larger surface by an interposed elastic ring or a similar member, whereby the guide bar is prevented from wear.

What is claimed is:—

1. A locking device of the class described comprising a guide member, two sleeves shiftably mounted thereon, a clamp member fixed to one of said two sleeves, a spring interposed between said sleeves, locking members arranged between said guide member and said clamp member and adapted to positively connect these parts in one direction of motion along said guide member, and a member interposed between said locking members and guide member adapted to distribute uniformly the pressure exerted by the former to the complete peripheral surface of the latter.

2. A locking device of the class described comprising a guide member, two sleeves shiftably mounted thereon, a clamp member fixed to one of said two sleeves, a spring interposed between said sleeves, locking members arranged between said guide member and said clamp member and adapted to positively connect these parts in one direction of motion along said guide member, and a resilient ring interposed between said locking members and said guide member and mounted thereon.

3. A locking device of the class described comprising a guide member, two sleeves shiftably mounted thereon, a clamp member fixed to one of said two sleeves, a spring interposed between said sleeves, locking members arranged between said guide member and said clamp member and adapted to positively connect these parts in one direction of motion along said guide member, a resilient ring interposed between said locking members and said guide member and mounted thereon, a recess in the other of said sleeves, said ring being held in place on said guide member within said recess.

4. A locking device of the class described comprising a guide bar, two sleeves shiftably mounted thereon, a tapered cap fixed to one of said sleeves, a spring interposed between said sleeves, a plurality of circumferentially

arranged locking members disposed between said tapered cap and the other one of said sleeve members to positively connect said cap and said other sleeve in one direction of motion along said guide member, and a slotted resilient ring underlying said locking members and surrounding said guide member.

The foregoing specification signed at Zurich, Switzerland, this 22nd day of November, 1930.
